UNITED STATES PATENT OFFICE

JOHN A. OVERALL, OF DE LASSUS, MISSOURI.

DESIGN FOR A KITCHEN-CABINET.

SPECIFICATION forming part of Design No. 27,020, dated May 4, 1897.

Application filed March 27, 1897. Serial No. 629,619. Term of patent 14 years.

To all whom it may concern:

Be it known that I, JOHN A. OVERALL, a citizen of the United States, and a resident of De Lassus, in the county of St. Francois and State of Missouri, have invented and produced 5 a new and original Design for Kitchen-Cabinets; and I do hereby declare that the following is a full, clear, and exact description of the invention, which will enable others skilled in 10 the art to which it appertains to make and use the same, reference being had to the accompanying drawings, which form a part of this specification.

My invention relates to a new and useful 15 design for a kitchen-cabinet; and it consists, essentially, in the peculiar shape and configuration given thereto.

In the accompanying drawings, Figure 1 is 20 a perspective view of a kitchen-cabinet made in accordance with my design. Fig. 2 is a vertical transverse section of the same.

In the said drawings the reference-numeral 1 designates a rectangular box divided by a 25 number of horizontal partitions and central vertical partition into a series of compartments 2, in which are located sliding drawers 3, provided with knobs 4. The numeral 5 designates the top of the box, provided at the rear corners with ornamental side pieces 6. Seated on the rear end of this top is a 30 vertical extension 7, the sides 8 of which are cut away at the front lower portions and curved at 9. The upper part of this extension is formed with compartments for containing sliding drawers 10, above which is a 35

compartment provided with a hinged front 12, having a mirror 13 in its front side. The lower portion of this extension is provided with a number of compartments and drawers and is also provided with a drop-down front 40 14, having a curved plate in the rear, and with ornamental lugs 15 at the rear corners. The numeral 16 designates pan-supports.

A cabinet constructed according to my design will present a very neat and ornamental 45 appearance, and which can be readily distinguished from other similar articles now on the market. More especially does the design consist in the peculiar configuration given to the sides of the extension whereby the upper portion of the latter is caused to overhang 50 the lower box. The front upper portion of the extension is provided with an ornamental strip 16, formed with rounded ends 17, and a number of intermediate triangular projections 18.

The numeral 20 designates a sieve located in one of the drawers contained in the box or lower portion 1 of the cabinet.

Having thus fully described my invention, 60 what I claim is—

The design for a kitchen-cabinet, substantially as herein shown and described.

In testimony that I claim the foregoing as my own I have hereunto affixed my signature 65 in presence of two witnesses.

JOHN A. OVERALL.
